O. HELPHINGSTINE

STEAM HEATING SYSTEM

Filed June 23, 1924

BY *Fred D. Hayn*

ATTORNEY.

UNITED STATES PATENT OFFICE.

OTTO HELPHINGSTINE, OF LOS ANGELES, CALIFORNIA.

STEAM-HEATING SYSTEM.

Application filed June 23, 1924. Serial No. 721,629.

To all whom it may concern:

Be it known that I, OTTO HELPHINGSTINE, a citizen of the United States, residing at Los Angeles, in the county of Los Angeles and the State of California, have invented a new and useful Improvement in Steam Heating Systems, of which the following is a specification.

My invention relates to an improved heating system, and improved process and trap for feeding automatically the condensate from steam used in industrial purposes and in heating systems to the boiler.

It is an object of my invention to provide an improved system and process whereby the condensate from steam may be automatically returned to the boiler against the pressure therein.

It is also an object of my invention to provide an improved process in which the air accumulated in a heating or other system is allowed to escape therefrom, to remove a portion of the live steam from said system, subject a portion of the water of condensation in said system to the pressure of said steam, neutralize the effect of said steam pressure, and permit the weight of said portion of the water of condensation to return same to the boiler against the steam pressure therein by balancing the head of two or more columns of the water of condensation in said system.

A still further object of my invention is to provide a novel steam trap which will function automatically to return the water of condensation in a heating or other system to the boiler against the pressure therein.

It is also an object of my invention to provide a steam trap with at least one fixed, flexible piston adapted to be actuated by a portion of the live steam in said system whereby the water of condensation accumulated in said system may be automatically returned to the boiler.

It is also an object of my invention to provide a trap in which a liquid piston is used to actuate one or more pistons movable in said trap against a portion of live steam in said system whereby the water of condensation in said system may be auto-

matically returned to the boiler against the pressure therein.

It is also an object of my invention to provide a receiver having an exterior pipe in which a liquid piston derived from the condensation of a portion of live steam may be housed, which liquid piston functions, together with said live steam, to permit the weight of a portion of the water of condensation accumulated in a heating or other system to return to the boiler by its own weight.

Another object of my invention is to provide a steam trap in which a receiver is used to house the water of condensation accumulated in a heating system, and in which receiver the live steam pressure is balanced until said receiver is practically empty, said water of condensation being automatically returned to the boiler against the steam pressure therein.

It is also an object of my invention to provide a heating or other system in which the condensate of a portion of the live steam from said system assists in causing the water of condensation in said system to be automatically returned to the boiler against the pressure therein. It is also within the province of my invention to provide a means for returning the surplus of said condensate to the boiler.

It is also an object of my invention to provide a novel form of heating or other system in which the head of two or more columns of water may function to return the water of condensation in said system to the boiler against the pressure therein.

It is also an object of my invention to provide a heating or other system in which a receiver does not function to return the water of condensation in such system to the boiler against the pressure therein until the water of condensation in said receiver has reached a level approximately equal to the level of a column of water in a pipe exterior to said receiver.

More specifically, it is an object of my invention to provide an improved heating or other system in which a receiver or trap is provided with one or more chambers

- containing fixed, flexible members or bellows, which are adapted to operate one or more valves to relieve the air and steam pressure therein, and prevent the formation of a 5 vacuum in said receiver or trap, said flexible members being adapted to be actuated by the live steam in said system and also a predetermined column of water of condensation derived from said live steam, 10 whereby said receiver or trap may function to return the water of condensation in said system to the boiler against the pressure therein.

It is also within the province of my invention to provide a pipe for conveying the 15 vapor, when the pressure formed within a receiver is relieved, to some distant point.

Further objects and advantages of my invention will become apparent as the 20 description thereof proceeds.

My invention is simple in character, efficient in operation, capable of being easily and inexpensively manufactured and not 25 easy to get out of order.

25 In the accompanying drawings similar reference characters denote similar parts. In the drawings,

Fig. 1 is a more or less diagrammatic view 30 of a portion of my improved system showing the trap or receiver for returning the water of condensation to the boiler,

Fig. 2 is an enlarged cross-sectional view 35 of the trap or receiver used with my system, and

Fig. 3 is a side view of the receiver or trap 40 shown in Fig. 2, illustrating the water gauge and air relief means with which said receiver or trap is provided.

Describing my invention more in detail, 45 1 indicates a receiver or trap placed at a distance above the water level in the boiler B. The steam main M conveys the live steam to the radiators R, the water of condensation from said radiators being returned to the boiler B by the return pipe 2, connection 3 and horizontal water of condensation connection 38.

At any convenient point in the steam main M a live steam connection 5 is connected thereto; a vertical pipe 6, the purpose of which will be more fully hereinafter 50 explained, connects the pipe 5 with the horizontal connection 38. The receiver or trap 1 is connected to the horizontal connection 38 by means of the vertical pipe 43, communicating with said receiver through its bottom 32. An external pipe 10, used to house the liquid piston, more particularly hereinafter described, is associated with the receiver 1 as shown in Fig. 1. A live steam pipe 7 connects the pipe 5 with the external pipe 10 by means of the conventional connection shown.

55 A shut off valve 42, shown in a conventional manner, is placed in the pipe 7, there being

a similar shut off valve 8 in the connection 38 and the valve 9 in the pipe 43. Suitable check valves 33 and 34 are placed in the connection 38, which valves may in practice take any form found desirable. It is also 70 obvious that the piping and connections shown in Fig. 1 may be varied as to size, length, and proportions, and I therefore do not propose to be limited to the exact details shown and described. 75

If desired, a well-known form of relief valve 4 may be placed anywhere in the return piping 2-3 to provide for the escape of the air in the system. A drain means 49 maybe provided for the pipe 10, if desired. 80

The receiver 1 may be provided with the usual water gauge 11, to indicate the level of the water of condensation accumulated in said receiver. A cover 31, bolted to the body of said receiver, by means of bolts 40 or any other securing means, is provided, but, if desired, said cover may be screwed in place, as will be clear.

An air relief, steam relief and vacuum 90 breaking housing 15 is mounted on the cover 31 in any suitable manner, a cover 14 being provided for closing said housing. A partition, provided with a relief passage 39, divides the housing 15 into upper and lower air, steam relief and vacuum breaking chambers 16 and 20 respectively. Said partition is provided with passages 44 and 45 controlled by a valve 17, which may take any form found in practice to be desirable. The valve 17 has a stem 19 adapted to be operated by another valve 18, the function of which will presently be explained. 100

In the receiver 1 are mounted in any preferred manner upper and lower chambers 105 21 and 22. The upper chamber 21 has a bottom 29 adapted to close said chamber, which bottom is secured to said chamber by any suitable securing means as bolts 30. A pipe 28 connects the two chambers, which pipe may be integral with the bottom 29 and the 110 top of the chamber 22 or may be secured to both in any manner preferred.

A suitable pipe 46 connects the exterior pipe 10 with the chamber 21, any preferred means for making the joint fluid tight being 115 provided for said pipe. It is clear, also, that any preferred way of connecting the chamber with the pipe 10 may be substituted for that shown and described and still remain within the province of my invention. A pipe 35 connects the bottom of the chamber 22 to the exterior pipe 10. 120

A bellows piston or flexible member 25 is fixed within the chamber 21, which piston may take any form found desirable. A similar piston 26 is fixed within the chamber 22, and a connection 36, whereby said pistons may be reciprocated in unison, is provided for rigidly connecting said pistons or members. The connection 36 may be solid, or 125 130

hollow as shown. The bottom of the chamber 22 is secured in place by means of suitable fastening means 47.

To permit the water of condensation from the system to enter the chamber 22 and passage 37 in the pipe 28, a port 27 is provided, a pipe connection 13, provided with a well-known form of float air relief valve 12, being connected to the passage 37 to relieve 10 the pressure in said connection.

Suitably secured to the top of the piston 25 is a steam valve 18, adapted to control the opening or port in the gland 41. Said valve 18 has a depression in the top thereof, in 15 which depression the stem 19 of the valve 17 is adapted to ride, so that when the valve 18 is lifted into contact with said stem 19 it lifts said stem and the valve 17 causing communication between the chamber 20 and the 20 chamber 16, establishing communication by means of the passages 44 and 45 with the outer atmosphere or by means of the pipe 48, Fig. 3, with the stack of the system or at any other convenient point, so that the steam 25 will not be allowed to enter the boiler room or any part of the building. The gland 41 may be screwed in or otherwise secured to the top of the chamber 21.

While I have shown the steam release and 30 vacuum breaking valve 17 as separate from the valve 18, it is clear that, if desired, the two valves may be made of one integral structure, capable of simultaneous operation.

It is also to be understood that I do not 35 limit myself to two chambers and two flexible members, but that a plurality of such chambers with a plurality of flexible members or pistons may be employed, it being vital that at least one such chamber with one member or piston be used.

In the operation of my apparatus and process, live steam from the boiler B flows through the main M to the radiators R or other apparatus used in industrial purposes, 40 and the water of condensation returns through the return pipe 2, pipe 3 to connection 38, the air in the system being relieved by means of the air valve 4.

The water in the boiler B stands at about 50 the level W, the check valves 34 and 33 respectively preventing said water and the water from the pipe 3 from entering the pipe 43. The water of condensation enters the pipe 43 and the receiver 1, the air therein being relieved through the pipe 13 and float air valve 12, the valve 17 also functioning for this purpose.

Live steam being admitted to the pipe 5 from the main M, it enters the pipe 7, pipe 60 10 and chamber 21 above the piston or flexible member 25. A portion of said steam will condense and form a liquid piston in said exterior pipe 10, the surplus of which is carried off by the pipe 6 and 65 returned to the boiler with the water of con-

denstation in the system. The live steam will exert a pressure on the top of the piston 25 and also on the liquid piston after it has been formed in the pipe 10. The pressure of the steam on the piston 25 will cause the same to 70 be depressed, opening the valve 18, the air in the chamber 20 being relieved by the valve 17 as hereinbefore explained. The passage 39 in the partition serves to equalize the pressure between the chambers 20 and 16. 75

The water of condensation formed by the condensation of the live steam in the pipe 10, as stated, forms the liquid piston, which will enter the pipe 35 and act against the lower side of the piston or flexible member 26, compressing whatever air may be trapped thereunder. The live steam pressure acting on said liquid piston and on the top of the piston 25, said steam pressure will become neutralized or balanced, and the head of the liquid piston in the pipe 10 and pipe 35 and below the piston 26 will cause the rigidly connected pistons 25 and 26 to move upwardly and close the valve 18. 80 85 90

The situation as now exists in the receiver 1 is substantially as follows:

A pressure substantially equal to that in the boiler acts on the top of the piston 25, and also a pressure substantially equal to that in the boiler below the piston 26. In addition to the boiler pressure acting beneath the piston 26, the head of the liquid piston in the pipe 10 acts on said piston 26, holding the valve 18 in closed position. 95 100

The water of condensation in the receiver 1, which had its level at about the level of the pipe 35, now enters the chamber 22 by means of the port 27, flows above the piston 26 and enters the passage 37, and below the piston 25 in the chamber 21, the air being relieved through the pipe 13 and air valve 12. The level of the water in the receiver 1 is now at approximately the line w'', shown in Fig. 1, which is slightly above the bottom of the pipe 7. 105 110

The moment the water reaches the level indicated, the pressure downward on both diaphragms or pistons becomes sufficient to open the valve 18, admitting live steam at practically boiler pressure to the receiver through the opening in the gland 41 and above the water in the receiver, practically equalizing the pressure existing in the boiler and the receiver. The water in the receiver 1 now falls by gravity and flows into the boiler. 115 120 125

There being now no pressure in the chamber 21 below the piston 25, the water in the passage 37 remains at its original level or higher, thereby holding the valve 18 open until the water level in the receiver 1 falls to the port or passage 27, the live steam then displacing the water in the passage 37. The pistons 25 and 26 now being relieved, move 130

upwardly, again closing the valve 18, the water of condensation once more rising to the level indicated, after which the operation is repeated.

5 It is clear that the valve 17 releases the steam pressure in the receiver after the valve 18 has closed. Since no atmospheric pressure must exist at any time in the passage 10 37, the pipe 13 and the air valve 12 are provided. It has been found in practise that only a half pound of steam pressure will be required to operate my trap.

It will be thus obvious that I have provided an apparatus that is simple in character, reliable and efficient in operation, thoroughly practical, and capable of being manufactured and installed at a low cost.

20 It is to be distinctly understood that I do not propose to be limited to the exact details of construction shown and described, and that the same may be modified throughout a wide range. I therefore reserve the right to make all modifications thereof that fall within the scope of the appended claims.

25 Having thus described my invention, what I claim as new and desire to protect by Letters Patent is:

1. In a steam heating system, in combination, a boiler, one or more radiators, a steam main connecting said boiler with said radiators, return piping connecting said radiators with said boiler, piping connecting directly said steam main with said return piping, and a set of liquid pistons 30 35 associated with said last mentioned piping and said return piping whereby the head of at least one column of water of condensation accumulated in said system may function with the steam pressure to return the water of condensation in the system to the boiler against the pressure therein.

2. In a steam heating system, in combination, a boiler, one or more radiators, a steam main connecting said boiler with said radiators, return piping connecting said radiators with said boiler, piping directly connecting said steam main with said return piping, and means including a set of liquid pistons, at least one of which is positioned above the water line in said boiler and associated with said last mentioned piping and said return piping whereby the head of at least one column of water of condensation accumulated in said system may function with the steam pressure to return the water of condensation in the system to the boiler against the pressure therein.

3. In a steam heating system, in combination, a boiler, one or more radiators, a steam main connecting said boiler with said radiators, return piping connecting said radiators with said boiler, means for removing a portion of the steam from said steam main and directly communicating the pressure thereof to said return piping, said

means forming a liquid piston, means for subjecting a portion of the water of condensation accumulated in said system to the pressure of said removed steam, and means associated with said last mentioned means whereby said steam pressure may become neutralized, thereby permitting the head of said portion of said water of condensation to return the water of condensation in said system to the boiler against the pressure therein.

4. In a steam heating system, in combination, a steam boiler, one or more radiators, a steam main connecting said boiler with said radiators, return piping connecting said radiators with said boiler, a steam trap connected to said return piping, a live steam line connecting said steam main with said return piping and said steam trap, and a set of liquid pistons associated with said steam trap and said live steam line whereby said live steam and the head of a portion of the water of condensation accumulated in said system may function to return the water of condensation in said system to the boiler against the pressure therein.

5. In a steam heating system, in combination, a boiler, one or more radiators, a steam main connecting said boiler with said radiators, return piping connecting said radiators with said boiler, a steam trap associated with said return piping, a set of liquid pistons associated with said trap and said steam main, means for connecting said steam main with said liquid pistons, one of said liquid pistons being connected with said return piping, means for removing the air from said steam trap, means for permitting the water of condensation accumulated in said system to enter said trap, means for subjecting the water of condensation entering said trap to the pressure of the live steam from said steam main, whereby the effect of the steam pressure in said boiler and said trap may be neutralized to permit the head of the water in said trap to cause the water of condensation in said system to be returned to the boiler against the pressure therein.

6. In a steam heating system, in combination, a boiler, one or more radiators, a steam main connecting said boiler with said radiators, return piping connecting said radiators with said boiler, a live steam connection connecting said steam main to said return piping, a steam trap connected to said return piping, an external pipe associated with said steam trap, means for connecting said live steam connection with said external pipe, a shut-off valve in said means, check valves in said return piping, a shut-off valve in said return piping, and a shut-off valve in the connection between said steam trap and said return piping, said steam trap and said external pipe function-

- ing to return the water of condensation accumulated in said system to the boiler against the pressure therein. 65
7. In a steam heating system, in combination, a boiler, one or more radiators, a steam main connecting said boiler to said radiators, return piping connecting said radiators with said boiler, a live steam connection between said steam main and said return piping, a trap associated with said return piping, means for housing a liquid piston associated with said trap, means for connecting said live steam connection with said means for housing said liquid piston, and a set of check valves for preventing the water in said boiler from returning to a substantial part of said return piping, said liquid piston, together with the pressure in said live steam connection and said trap functioning to return the water of condensation in said system to said boiler against the pressure therein. 70
8. The process of returning the water of condensation formed in a heating system to the boiler which consists in removing a portion of the live steam in said system, causing a portion of said removed steam to be condensed, subjecting the water of condensation thus formed to the pressure of said removed steam, causing the effect of said pressure to become neutralized, whereby, the head of said water of condensation thus formed will return the water of condensation accumulated in the system to the boiler against the pressure therein. 75
9. The process of removing the water of condensation from the radiators of a steam heating system and returning it to the boiler which consists in permitting the air accumulated in said system to escape therefrom, removing a portion of the live steam in said system, causing a portion of said removed steam to condense, subjecting the water of condensation thus formed to the pressure of said removed steam, subjecting the water of condensation in said system to said live steam pressure, neutralizing the effect of said steam pressure, whereby the head of the water of condensation formed by the condensation of said live steam will return the water of condensation to the boiler against the pressure therein. 80
10. The process of returning the water of condensation from the radiators of a steam heating system to the boiler which consists in permitting the air accumulated in said system to escape therefrom, removing a portion of the live steam from said system, subjecting a portion of the water of condensation accumulated in said system to the pressure of said removed steam, neutralizing the effect of said steam pressure by balancing the head of two or more columns of water, and permitting the weight of said portion of the water of condensation to return said water of condensation to the boiler against the steam pressure therein. 85
11. In a steam heating system, in combination, a boiler, one or more radiators, a steam main connecting said boiler with said radiators, a return pipe connecting said radiators with said boiler, a receiver associated with said return pipe, a live steam connection from said steam main to said receiver, and an exterior pipe connected to said receiver and said live steam connection, said receiver functioning to return the water of condensation accumulated in said system to the boiler against the pressure therein when a level is reached in said receiver approximately that of the water of condensation in said exterior pipe, the steam pressure in said receiver causing the water in said exterior pipe to remain suspended, thereby permitting said water of condensation to return to the boiler. 90
12. In a steam trap, in combination, a receiver, upper and lower chambers mounted in said receiver, a connection between said chambers, a flexible member mounted for reciprocation in each of said chambers, means for rigidly connecting said members whereby they may be reciprocated in unison, said receiver and said connection being provided with means for relieving the air pressure therein and also preventing the formation of a vacuum therein, means for subjecting the flexible member in said upper chamber to live steam pressure, means for subjecting the flexible member in said lower chamber to live steam pressure and also to the head of a column of water associated with said steam trap, and means for permitting the water of condensation to enter said trap, said water of condensation when entering said communication between said chambers, after said water of condensation has reached a certain level, functioning to equalize the pressure on said flexible members, said live steam permitting the pressure on said flexible members to become unequal after said water of condensation has been removed from said trap by gravity. 95
13. In an apparatus of the class described, in combination, a receiver, upper and lower chambers mounted in said receiver, an exterior pipe associated with said receiver, connections between said exterior pipe and each of said chambers, a live steam pipe adapted to conduct live steam to said exterior pipe and to said upper chamber, said exterior pipe being adapted to house water of condensation formed by said live steam, a pipe connected to said live steam connection for carrying off the surplus water of condensation from said live steam connection, and means adapted to be moved in said chambers, which means 100
- 103
- 110
- 115
- 120
- 125

functions to permit the water of condensation conveyed to said receiver to flow therefrom by gravity.

14. In a steam trap, in combination, a receiver, upper and lower chambers positioned in said receiver, a pipe positioned exterior to said receiver and connected to each of said chambers, means for conveying live steam to said pipe and said upper chamber, 10 said pipe being adapted to receive the water of condensation formed by said live steam, thereby forming a head of water in said pipe, a flexible member fixed in each of said chambers, and means for permitting water 15 of condensation to enter said receiver, the flexible member in said lower chamber being subjected to the pressure of said live steam and said head of water, while the flexible member in said upper chamber is subjected 20 merely to the pressure of said live steam, said flexible members when subjected to the pressure mentioned functioning to permit the water of condensation in said receiver to flow therefrom by its own weight.
15. In a steam trap, in combination, a receiver, upper and lower chambers positioned therein, a piston adapted to be reciprocated in said upper chamber a piston adapted to be reciprocated in said lower chamber, means 30 for connecting said pistons whereby they may be reciprocated in unison, means for conveying live steam to said upper chamber above the piston therein, means for subjecting the piston in said lower chamber to the 35 head of a column of water and also to said live steam pressure, and means for neutralizing the effect of said steam pressure whereby the water of condensation in said receiver may be removed therefrom by its 40 own weight.

16. In a steam trap, in combination, a receiver, means for permitting water of condensation to enter said receiver, means associated with said receiver for forming a liquid piston, means for subjecting the water of condensation in said receiver to live steam pressure, means for subjecting said liquid piston to said live steam pressure, and means 45 whereby the pressure of the live steam operating on said liquid piston may be neutralized, permitting said water of condensation to flow from said receiver by its own weight.

17. In a steam trap, in combination, a receiver, means for permitting water of condensation to enter said receiver, means associated with said receiver for forming a liquid piston, means for subjecting the water of condensation in said receiver to live steam 50 pressure, means for subjecting said liquid piston to said live steam pressure, means whereby the effect of the live steam pressure operating on said liquid piston may be neutralized, permitting the water of condensation to flow from said receiver by its own 55 weight.

weight, and means for removing the surplus water of condensation formed by said live steam.

18. In a steam trap, in combination, a receiver, at least one chamber positioned in 70 said receiver, means associated with said receiver for forming a liquid piston, a flexible member mounted in said chamber or chambers, means for subjecting said flexible members to the pressure of said live steam, means 75 for subjecting said liquid piston to the pressure of said live steam, means whereby said flexible members may be also subjected to the pressure of said liquid piston, and means for neutralizing the effect of said live steam 80 pressure whereby the water of condensation in said receiver may flow therefrom by its own weight.

19. In a steam trap, in combination, a receiver for holding a portion of water of condensation formed in a heating system, at 85 least one chamber mounted in said receiver, means for relieving the air pressure in said receiver, means for preventing the formation of a vacuum in said receiver and said chamber or chambers, means for conveying live steam to said receiver, and means associated with said receiver and said chamber or chambers for permitting the water of condensation to flow from said receiver by 90 its own weight.

20. In a steam trap, in combination, a receiver, upper and lower chambers positioned in said receiver, a fixed bellows piston mounted in each of said chambers, a rigid connection between said pistons, an air and steam relief housing associated with said receiver, means in said housing and associated with the piston in said upper chamber for relieving the air and steam pressure in 105 said receiver, means for subjecting one of said pistons to live steam pressure and the other to said live steam pressure and that of a liquid piston associated with said receiver, and means for admitting water of 110 condensation to said receiver, said pistons, live steam pressure and liquid pistons functioning to permit said water of condensation to flow from said receiver by its own weight.

21. In a steam trap, in combination, a receiver, one or more chambers mounted in said receiver, one or more pistons adapted to be reciprocated in said chamber or chambers, means for subjecting one of said pistons to live steam pressure, and means for neutralizing the effect of said live steam pressure, thereby permitting the water of condensation in said receiver to flow therefrom by its own weight.

22. In a steam trap, in combination, a receiver for holding water of condensation, upper and lower chambers mounted in said receiver, a bellows piston mounted in each of said chambers, means for rigidly connect- 130

ing said pistons whereby they may be reciprocated in unison, means for establishing communication between said chambers, each of said chambers being provided with means for establishing communication with said receiver, a valve for controlling one of said means, means for permitting live steam to act against one of said pistons, means for permitting the head of a liquid piston and

said live steam pressure to act against the other of said pistons, an air and steam valve permitting the air and steam to escape from said receiver, and a pipe for conveying said air and steam to a distant point, said pistons, and live steam pressure functioning to permit said water of condensation to flow from said receiver by its own weight.

OTTO HELPHINGSTINE.
